PISTON PUMP

Application filed December 13, 1928, Serial No. 325,867, and in Sweden December 22, 1927.

This invention relates to piston pumps especially for rarefying or compressing air or other gaseous fluids.

Piston pumps for such purposes are known which are provided with spring-loaded suction and pressure valves combined with controlling means in mechanical connection with the piston or its driving means and adapted to relieve the valves from the pressure of the springs when the piston is in or near to its end positions, the valves being in such manner positively operated to open and close the inlets and outlets in due time. Such pumps have the advantage that the clearance of the pump cylinder can be reduced practically to nil, and they may thus be used to create very high vacua or very high pressures with one cylinder only. A drawback of such pumps as hitherto constructed was, however, that they could not advantageously be carried out with double-acting pistons.

The chief object of this invention is to improve piston pumps of the kind above referred to so as to make it possible to construct them double-acting while maintaining the advantage of a minimal clearance of the cylinder at both ends of the latter.

The invention consists, chiefly, in a double-acting piston pump, comprising a cylinder, spring-loaded loose covers at both ends of said cylinder forming the outlet valves of the pump, a hollow piston having inlet valves in both ends, and a hollow piston rod connecting the interior of the piston with the suction conduit of the pump.

Another object of the invention is to provide improved means for loading and unloading the inlet and outlet valves of the pump as will be set forth in detail in the following description of the invention.

In the accompanying drawings I have shown, in part diagrammatically, one embodiment of my invention.

Fig. 1 is a longitudinal central section of double-acting vacuum pump according to the invention, the piston being shown in one of its end positions.

Fig. 2 shows on a larger scale a longitudi-

nal central section of the piston and one end of the cylinder.

Fig. 3 is a cross-sectional view on the line III—III of Fig. 2; and

Fig. 4 is a similar view to that shown in Fig. 2 with the piston shown in a position in which it is at a distance from the right end of the cylinder.

Referring now to the drawings, 1 is the pump cylinder and 2 the pump piston which in usual manner is provided with tightening rings 3 disposed in grooves in the mantle surface of the piston. The piston 2 is adapted to be driven from the main shaft 4 by means of a disc crank 5, a connecting rod 6 and a link 8 journalled on a pin 7 and being at its free end provided with a toothed bow 9 engaging a rack 10 secured to one end of the piston rod 11 and forming an extension of the latter. The piston rod 11 which is composed of two parts, one on each side of the piston 2, is hollow, its channel being in open connection with the hollow 12 of the piston on one side and with a chamber 13 in an extension 14 of the pump casing on the other side. The extension 14 is provided with a flanged socket 15 adapted to be connected with the vessel to be evacuated. Outside the open plane ends of the cylinder 1 covers 16, 16 are provided which form the pressure or outlet valves of the pump and for such purpose are movable to and from the open ends of the cylinder. Each cover 16 has a hollow extension 17 which closely fits to the corresponding portion of the piston rod 11 and is movable in a corresponding boring in the pump casing. The latter forms two hoods 18 which enclose each one of the covers 16 and are connected with each other by a channel 19 provided with a flanged socket 20. The latter is, when the pump is used for evacuating purposes, in connection with the open air while it is connected with the pressure conduit of the pump when the pump is acting as a compressor. In each end wall of the piston 2 two suction or inlet valves 21 and 22 respectively are provided, said valves being loaded by springs 23 and 24 respectively tending to close the valves. The valve stems are guided by straps 23^a and 24^a re-

spectively and are at their inner ends provided with heads 25 and 26 respectively.

The cylinder covers 16, 16 forming the pressure valves are each loaded by a laminated plate spring 27 secured to a swingable arm 29 journalled on a pin 28 and having an inner furcated end which engages the outer side of the cover 16. The outer ends of the springs 27 engage recesses in two adjustable heads 30 on a push rod 31 journalled in guides 32 in such manner that it can be moved parallelly to the piston. The push rod 31 which in this case forms a member controlling the load of the pressure valves 16 is by means of a link 33, a lever 35 rotatably journalled on a pin 34, and a link 36 connected to the arm 8 in such manner that it is moved to the right, Fig. 1, when the piston 2 moves to the left, and vice versa. When the push rod 31 is moved to the right, Fig. 1, the right spring 27 will press the right cover or pressure valve 16 against its seat, i. e. the right end of the cylinder 1, while the left pressure valve 16 simultaneously is relieved from the load of the left spring 27. When the rod 27 is moved to the left, the left spring 27 will press the left pressure valve 16 against its seat while the right pressure valve 16 at the same time is relieved from the load of the right spring 27. By adjusting the heads 30 on the rod 31 and the connecting point of the link 36 with the arm 8 in suitable manner it is possible to attain that the relieving of the pressure valves from their loads takes place in the desired moments in relation to the movements of the piston 2.

The controlling members of the suction valves 21 and 22 consist in the embodiment shown of two levers 37 rotatably journalled on two parallel pins 38 secured in arms 39 in the interior of the piston. The outer end of said levers are coupled together by means of two springs 40 which are essentially stronger than the springs 23 and 24 of the suction valves. The levers 37 are shifted into the position shown with full lines in Fig. 2 immediately before the piston 2 reaches its right end position, by means of a pin 41 secured to a fix rod 42 extending through the hollow piston 11 and secured to the outer wall 43 of the chamber 13. The outer ends of the levers 37 are in this position in contact with the stem heads 26 of the suction valves 22 and open by the action of the strong springs 40 said valves as soon as the piston begins its movement to the left (see Fig. 4). The levers 37 are thereafter immediately before the piston reaches its left end position shifted to the position shown by dotted lines in Fig. 2, by means of a head 44 on a fix sleeve 45 secured to the wall 43 and surrounding the rod 42. By said latter shifting the outer ends of the levers 37 are brought into contact with the stem heads 25 of the suction valves 21 and open the latter by means

of the strong springs 40 as soon as the piston 2 begins its movement to the right. It is to be noted that the shifting of the levers 37 to the one or other end position is performed by the springs 40 as soon as they by the action of the member 41 or 44 have been turned over their middle position, i. e. the position in which they are parallel to each other. By means of two nuts 46 and 47 which are accessible after the removal of the cap 48 the rod 42 and the sleeve 45 and thus also the members 41 and 44 can be adjusted so that the shifting of the levers takes place in the desired moments in relation to the movements of the piston 2.

In the position shown in Figs. 1 and 2 the piston 2 is in its right end position in which the right cylinder cover or pressure valve 16 is somewhat lifted from the right end of the cylinder 1 and closely fits to the plane right side of the piston 2. The suction valves 22 are, therefore, held closed though the spring-loaded levers 37 engage the spindle heads 26. When the piston 2 then begins its movement to the left the rod 31 is at the same time moved to the right. The right spring 27, Fig. 1, will then exert a pressure on the right cylinder cover 16 so that the latter is caused to follow the piston until it is pressed against the right end of the cylinder 1. The spring load is thus brought to act on the right pressure valve 16 immediately when the piston begins to move towards the left so that said pressure valve is at once safely closed. Immediately after the closing of the right cover or valve 16 the springs 40 acting on the levers 37 open at the continued movement of the piston 2 to the left the suction valves 22 (see Fig. 4) while overcoming the tension of the weaker valve springs 24. The suction valves 22 are thus positively opened without the assistance of any suction action thereon by the piston. During the continued movement of the piston 2 to the left the air can then be sucked into the right chamber of the cylinder 1 from the vessel to be evacuated, said air flowing through the socket 15, the chamber 13, the hollow piston rod 11, the chamber 12 and the open suction valves 22. At the same time the air sucked in by the piston into the left cylinder chamber during the preceding stroke is compressed and driven out between the left end of the cylinder wall and the left cover 16 which now is relieved from the load of the spring 27, said air flowing into the open air through the channel 19 and the socket 20.

Immediately before the piston 2 reaches the left end position of its stroke the levers 37 hit the head 44 and are by said head and the springs 40 shifted into the position shown by dotted lines in Fig. 2 whereupon the levers 37 will rest on the stem heads 25 of the suction valves 21. Said valves are, however, not immediately opened by the pressure of the

springs 40 in as much as they already before the shifting of the levers 37 had come into engagement with the left cylinder cover 16. When the pump piston 2 finally reaches its left end position it has lifted the left cylinder cover 16 somewhat from the left end of the cylinder wall. In this moment the left cover 16 rests against the piston 2 in the same manner as before the right cover rested against the piston (Fig. 2). When the piston 2 then begins its stroke towards the right the rod 31 is simultaneously moved to the left thus causing the left spring 27 (Fig. 1) to exert a pressure against the left cylinder cover 16 so that the latter follows the piston until it is pressed against the left end of the cylinder 1. The spring load is accordingly caused to act on the left pressure valve 16 immediately when the piston begins to move towards the left so that said pressure valve is at once closed. Immediately thereafter the springs 40 open by means of the levers 37 the suction valves 21 without any suction action of the piston being necessary for such purpose. During the movement of the piston towards the right air is sucked in through the socket 15, the chamber 13, the hollow piston rod 11, the chamber 12 and the open suction valves 21 into the left chamber of the cylinder. At the same time the air contained in the right chamber of the cylinder is forced out between the right end of the cylinder wall and the right cylinder cover 16 which now is relieved from its spring-load, whereupon said air escapes through the channel 19 and the socket 20 to the open air. The pump described is accordingly double-acting and has also the advantage that it has practically no clearance in the cylinder.

The embodiment above described and shown in the drawing is only an example and can, of course, be modified in several respects without departing from the principle of the invention. The means illustrated for driving the piston are not essential for the invention. For the toothed bow 9 and the rack 10 other equivalent means such as a steel band connection between the rod 11 and a smooth driving bow may be used. When the pump is to be used as compressor, the socket 20 is connected to the vessel in which the gas is to be compressed. In such case it is, of course, necessary to tighten the caps 18 at the pins 28 so that the gas is prevented from leaking at said place.

What I claim is:—

1. A double-acting piston pump, comprising a cylinder having open plane ends, spring-loaded loose covers adapted to close said ends and forming outlet valves, a hollow piston, spring-loaded suction valves in the end walls of said piston, means for positively opening some of said suction valves against the action of their spring-load when the piston is in or near to any of its end positions, and a hollow

piston rod connecting the interior of the piston with the suction conduit of the pump.

2. A double-acting piston pump, comprising a cylinder, spring-loaded loose covers at the ends of said cylinder forming outlet valves, a hollow piston, spring-loaded suction valves in the end walls of said piston, and swingable levers in the interior of the piston adapted to open some of the suction valves against the action of their spring-load when the piston is in or near to any of its end positions.

3. A double-acting piston pump, comprising a cylinder, spring-loaded loose covers at the ends of said cylinder forming outlet valves, a hollow piston, spring-loaded suction valves in the end walls of said piston, spring-loaded levers rotatably journaled in the interior of the piston, and fix stops adapted to cooperate with said levers so as to open some of the suction valves when the piston is in or near to any of its end positions.

4. A double-acting piston pump, comprising a cylinder, spring-loaded loose covers at the ends of said cylinder forming outlet valves, a hollow piston, spring-loaded suction valves in the end walls of said piston, spring-loaded levers rotatably journaled in the interior of the piston, fix stops adapted to cooperate with said levers so as to open some of the suction valves when the piston is in or near to any of its end positions, and means for adjusting the position of said stops.

5. A double-acting piston pump, comprising a cylinder, loose covers at the ends of said cylinder forming outlet valves, springs adapted to exert a pressure on said covers, a hollow piston, suction valves in the end walls of said piston, driving means for the said piston and means operated from said driving means and adapted to operate the springs of the end covers so as alternately to load and unload said covers.

6. A double-acting piston pump, comprising a cylinder, loose covers at the ends of said cylinder forming outlet valves, springs adapted to exert a pressure on said covers, a hollow piston, driving means for said piston, a push rod mechanically connected to said driving means and adapted to operate said springs so as alternately to load and unload said covers, and means for adjusting the operation of said push rod.

In testimony whereof I have signed my name.

HJALMAR FRIBERG.
